CLAIM

The ornamental design for a gaming machine button panel, as shown and described herein.

DESCRIPTION

FIG. 1 is a front perspective view of a gaming machine button panel of one embodiment of our new design.

FIG. 2 is a front view of the gaming machine button panel of FIG. 1.

FIG. 3 is a top view of the gaming machine button panel of FIG. 1.

FIG. 4 is a bottom view of the gaming machine button panel of FIG. 1.

FIG. 5 is a left side view of the gaming machine button panel of FIG. 1.

FIG. 6 is a right side view of the gaming machine button panel of FIG. 1.

FIG. 7 is a front perspective view of a gaming machine button panel of another embodiment of our new design.

FIG. 8 is a front view of the gaming machine button panel of FIG. 7.

FIG. 9 is a top view of the gaming machine button panel of FIG. 7.

FIG. 10 is a bottom view of the gaming machine button panel of FIG. 7.

FIG. 11 is a left side view of the gaming machine button panel of FIG. 7; and,

FIG. 12 is a right side view of the gaming machine button panel of FIG. 7.

The portions shown in phantom are not part of the claimed design.
